A. SAXE

TOOTHBRUSH

Filed Oct. 20, 1925

INVENTOR

Alexander Saxe
BY
Arthur Phelps Marr
ATTORNEY

UNITED STATES PATENT OFFICE.

ALEXANDER SAXE, OF NEW YORK, N. Y.

TOOTHBRUSH.

Application filed October 20, 1925. Serial No. 63,573.

The device, the subject of this invention, is a tooth brush having a detachable handle.

The object of this invention is to provide a tooth brush, wherein the handle is in rotatable relation to the head and wherein the head may be removed from the handle or holding member and a new head substituted.

A further object of the invention is to construct a tooth brush in such a manner that the handle may be made of precious or semi-precious metals or materials and may be used for a long period of time, new heads or bristle carrying parts being substituted whenever desired, just as razor blades are substituted in safety razors.

A further object of the invention is to encourage frequent changes of tooth brushes for sanitary reasons, a change that is neglected beyond the point of correct sanitation, due to the fact that good tooth brushes are expensive and are therefore, retained as long as they are considered useful, even though their use may endanger the health of the user.

A further object of the invention is to produce a tooth brush having a handle constructed and adapted for long and continuous service and comparatively cheap bristle carrying parts, which may be discarded at no great expense and a further object of the invention is to construct a brush fulfilling the objects above set forth and yet of such simple construction and operation that it may be successfully used by even those entirely lacking mechanical knowledge.

With these and other objects in view, the following is what I consider a good means of carrying out this invention and the accompanying drawing should be referred to for a complete understanding of the specification which follows:—

In the drawing:—

Fig. 1, is a side elevation of my device assembled.

Fig. 2, is a top plan view.

Fig. 3, a sectional view on the line 3—3 in Fig. 2.

Fig. 4, is an enlarged view of a portion of the handle.

Fig. 5, an enlarged view of the clip or head holding part.

Fig. 6, is a top plan view of the bristle carrying head.

Similar reference numerals indicate like parts in all the figures where they appear.

The handle of my device, may, as shown in the drawing, be formed of two parts, as indicated at 10 and 11. The part 10 is nothing more or less than a grip member and may be of hollow metal, of celluloid or other suitable material. The part 11 is the shank member and should be of steel, bent as shown at 12 and I prefer that the angle of bend should be about that shown. The portion 13 of the blade 11 is flattened and is provided with a perforation as shown at 14 in Fig. 4, and adjacent to this perforation is a downward projection as shown at 15 in Fig. 4, this projection being formed integral with the shank member and it may be formed by forcing the metal of the shank member downward.

Through the perforation 14, a rivet 16 is passed. The rivet passing through the member shown in Fig. 5 and which I will refer to is the clip 17. This clip is a strip of preferably spring steel, provided with two inward projections as shown at 18 and 19 in Fig. 3. This clip is also provided with a perforation 20, a part of the wall of which is cut away to form an arc shaped recess 21, as shown in Fig. 5 and in which the projection 15 will operate.

The head of the brush is provided at its mid-length with a shallow recess 22, which extends not only across the top of the head but down the sides thereof to a limited extent. The depth of the recess is approximately equal to the thickness of the metal from which the clip 17 is formed and I may provide a shallow annular recess 23 at mid-center of the head 24, which will receive the head portion of the rivet 16. The rivet 16 secures the shank 13 and clip 17 firmly together, care being taken that these parts be so secured that they will not turn easily, one on the other, thus avoiding accidental displacement of the parts.

The operation of my device may be well understood from the description and its construction. Attention is called to the fact, however, that when the parts are assembled as described, the handle member may be partially rotated out of the right angled or transverse position, shown in Fig. 2, to a position approximately that of the dotted lines 25 and the position at the other side of the center or right angled position will be equal to that shown by the dotted lines 25.

Having carefully and fully described my

invention, what I claim and desire to obtain is:—

A tooth brush comprising a brush head provided with an indent at each side thereof, 5 a spring clip having up-set projections adapted to engage in said indents, said clip being provided with a sector shaped perforation and a handle connected to said clip

and means formed in said handle adapted to enter the sector shaped perforation in said ¹⁰ clip for checking the relative movement of said handle and said clip.

Signed in Cuyahoga County, and State of Ohio, this 13th day of October, 1925.

ALEXANDER SAXE.
